UNITED STATES PATENT OFFICE.

WILLIAM C. HOOD, OF CHICAGO, ILLINOIS.

ELECTRIC FAN.

1,214,163.

Specification of Letters Patent. Patented Jan. 30, 1917.

Application filed October 8, 1914. Serial No. 865,615.

To all whom it may concern:

Be it known that I, WILLIAM C. Hood, a citizen of the United States, residing at Chicago, in the county of Cook and State of Illinois, have invented certain new and useful Improvements in Electric Fans, of which the following is a specification.

My invention relates to electric fans, and more particularly to fans adapted to distribute the current of air from a deflector or the like.

Among the salient objects of the invention are to provide a construction of the character above referred to, in which the air is drawn toward the deflector and returned at a predetermined level; to provide a fan which can be mounted adjacent the ceiling or the side wall and the course of the deflected air governed to cover a predetermined area; to provide a fan in which the deflector plate is positioned in the rear of the fan and the polarity of the motor and the shape of the fan blades reversed from the ordinary construction so that the air is sucked in against the deflector plate; to provide means for adjustably regulating the angle at which the air is deflected, whereby the radius within which the fan produces air currents can be increased or lessened to correspond with the size of the room or the area which it is desired shall be regulated; to provide a mechanism of this character which can be suspended from the ceiling or positioned at the side wall and utilized to fumigate or perfume the room by positioning the perfume or fumigating substance in the path of the air which is sucked against the deflector plate and returned back to the desired portion of the room; to so construct the deflector plate that it may be used with fans of standard size and shape; to so construct and arrange the parts as to render the motor practically invisible when viewed from any point except the back or top of the device. The device, therefore, is extremely compact and occupies very little more space than would be occupied by the fan and motor alone; and in general to provide an improved fan of the character first above mentioned which can be economically manufactured and will efficiently perform these various objects.

In the drawings Figure 1 is a side elevation, showing a fan structure embodying my invention, attached to the ceiling of a room. Fig. 2 is a top plan view showing a

slightly modified construction. Fig. 3 is a cross section on the line 3—3 of Fig. 2.

In various fans previously constructed, attempts have been made to avoid the unpleasant and disadvantageous effects of the direct blast of air from the fan by placing perforated shields or the like in front of and around the fan blades. Such shields, however, tended to reduce the volume of the air current produced by the blades, and were further deficient in that no provision could be made for regulating the area of the surface acted upon without tending to decrease the efficiency of the fan.

In the present construction I have obtained the regulation of the air currents by a simple and efficient construction and without materially diminishing the volume of the air blast.

Referring first to the construction shown in Fig. 1 of the drawings, 1 designates the fan, having a plurality of blades 2 connected to the shaft 3 of the motor 4. The latter is connected by wire 5 with a suitable source of current, and the electrical connection with the motor is controlled by a switch 6. When the fan is suspended from the ceiling as shown in Fig. 1, I preferably connect this switch with an extension cord 7 adapted to extend over the edge of the deflector 8 to a point where it can be conveniently operated. The polarity of the motor 4 is reversed from that of the ordinary type of fan, and this together with the construction of the blades 2 results in the fan sucking the air in toward the deflector plate 8. The central portion of this plate is approximately frusto conical and curves outward gradually toward the edge to form a rim portion 8', but as shown in Figs. 1 and 3 the marginal portions 9 are preferably slightly deflected downwardly so that the deflected air, while having a general direction transverse to the axis about which the fan revolves, is returned slightly toward the space from which it is drawn. By increasing the angle of the marginal portions 9, the area covered by the deflected air is decreased, while a decrease in the angle of the marginal portions will result in the deflected air passing in a more nearly horizontal position. This arrangement, whereby the air is drawn upwardly and deflected in a horizontal position from a plate suspended from the ceiling, is an important feature of my invention, since it throws the air out

above the plane of the occupants of the room or can be used to cover any predetermined area accordingly as the marginal portions are more or less sharply inclined.

5 In the modification disclosed in Figs. 2 and 3, means are provided for changing the incline of the marginal portions without reconstructing the main portion of the deflector plate. As shown in Fig. 3 the bead 10 of the deflector plate receives a complementary bead 11 formed in a removable band 12. The latter is constructed preferably in the shape of a split collar, the meeting ends 13 and 14 of which are provided with lugs 15 and 16 through which a bolt 17 extends. By tightening or loosening the winged nut 18, the ends of the band 12 are adjusted toward or from each other. The band can be adjusted in this manner or entirely removed and a band of different configuration substituted. It is to be noted that the removable band 12, above mentioned, can be applied to the beaded portion 10 of the deflector plate without structurally changing the latter, although in some instances it may be found advisable to position the eyelets 19, 20 and 21, to which the supporting chains 22 are secured, at points inside the marginal rim, as indicated in

25 Fig. 2.

It is obvious that the regulation of the area controlled by the deflected air by means of the inclined surface 9 and the band 12, would be of material value if the fan were mounted on the side wall. However, as previously stated, I preferably suspend the fan and its deflector plate from the ceiling and at a level above that of the occupants of the room. This not only decreases the liability of the fan injuring anyone but permits of the air being drawn to a point near the ceiling and returned at any desired level between the ceiling and the floor; and further, if it is desired to perfume or fumigate the room, it is only necessary to position the powder or other substance in the path of the incoming air to have it distributed equally at the desired level.

It will be observed that my device, especially in the form shown in Figs. 2 and 3 is not simply a deflector but is, practically speaking, a reflector as well for it not only throws the up blast laterally outward but is capable, when provided with a band 12 as indicated, of returning it in a downward as well as outward direction. My device is thus capable of creating an indirect air stream, the force of which is greatly lessened and the effective area greatly increased. Besides this the individual impulses or air waves created by the blades of the fan are merged together in striking the deflector plates and are converted into a smooth and continuous air stream.

65 It will be noted also that on account of

the frusto conical shape of the deflector at the center, space is afforded for receiving the motor. The configuration and arrangements are such that the motor is not only well protected from the sides, but is practically invisible from all points except the top or back of the device. While this characteristic is not essential, I would call attention to the fact that in the present embodiment of the invention there is a circular opening at the base of the conical portion of the deflector and that this opening is closed by the bottom of the motor. This forms a convenient and inexpensive manner of constructing and assembling the parts and furnishes a neat appearance. By forming an annular shoulder 22 upon the motor the larger diameter whereof is larger than the diameter of the circular opening at the bottom of the deflector, the motor may rest as it were in a socket, and for a device of the ceiling or suspended type no actual fastening devices are necessary.

It will be seen that my apparatus produces indirect ventilation in the sense that it first creates a current of air in a direction opposite or approximately opposite to that ultimately desired, and that thereafter the air stream is gradually diverted, first traveling radially outward in all directions and ultimately traveling in a direction almost opposite to the initial direction, especially when a band or hood such as the one illustrated in Figs. 2 and 3 is present. This tempers the air stream and increases its effective area in the manner already described.

While I have shown and described a particular construction of deflector plate 8 and band 12, it is obvious that various changes in construction and arrangement of parts could be made without departing from the scope of my invention, and I do not desire to limit the invention except as specified in the appended claims.

I claim as my invention:

1. The combination with a fan, of a deflector plate positioned in rear of said fan, said deflector plate having a substantially wide marginal portion terminating in a rounded bead portion and an inclined band secured to said bead portion for governing the area controlled by the deflected air currents.

2. The combination with a fan, of a deflector plate positioned in rear of said fan, said deflector plate having a substantially wide marginal portion terminating in a rounded bead portion, an inclined band secured to said bead portion for governing the area controlled by the deflected air currents, said band being detachable from the bead portion.

3. In an electric fan and in combination, a deflector plate having a truncated conical portion with the side of the cone concave, a

rim and an intermediate portion of substantial extent merging into the concave cone and the rim, a motor having its major portion located at the rear side of the plate in the chamber formed by the conical portion and a fan located coaxial of the plate in advance of the front side thereof.

4. In an electric fan and in combination, a deflector plate having a truncated conical central portion with an opening through the end of said truncated portion substantially co-extensive in area with said end and a deflecting portion of material extent at the

base of the cone, a motor having a casing, said motor having its major portion located 15 in the chamber formed at the rear of the plate by the conical portion thereof and an end of its casing exposed through said opening in the plate and substantially closing the same, and a fan arranged coaxial of the 20 plate in advance of said exposed end of the motor casing.

WILLIAM C. HOOD.
